UNITED STATES PATENT OFFICE.

GEORGE F. HAVENS, OF STERLING, ILLINOIS.

POSTER-DISPLAY MACHINE.

1,130,084.

Specification of Letters Patent.

Patented Mar. 2, 1915.

Application filed March 24, 1913, Serial No. 756,345. Renewed December 24, 1914. Serial No. 878,942.

To all whom it may concern:

Be it known that I, GEORGE F. HAVENS, a citizen of the United States, residing at Sterling, in the county of Whiteside and State of Illinois, have invented certain new and useful Improvements in Poster-Display Machines, of which the following is a specification.

My invention has reference to machines for displaying posters and advertising matter, and it is specially designed for use in connection with moving picture shows. In this class of business it is necessary to change the advertising matter at the front of the show-house daily, and the present means for accomplishing this are quite crude and unsatisfactory.

By the use of my machine it is possible to display a series of pictures or cards in rotation, in such a manner as to attract the attention of the passer-by, and to remove one set of advertising matter and replace it with another conveniently and quickly.

In the drawings: Figure 1 is a front elevation of my invention, with the frame removed, and with a poster in place therein. Fig. 2 is a side view with the side of the receptacle removed. Fig. 3 is an enlarged detail of the ends of the clamp-plates 17 and 22. Fig. 4 is an inner end view of the sockets 15 and 26, with the clamp-plates shown in cross-section. Fig. 5 shows the clamp-plates in cross-section, in closed position. Fig. 6 is a similar view thereof, open. Fig. 7 is a detail of the segment gear 38 and pinion 39.

Similar parts are indicated by corresponding reference numbers throughout the several figures.

1 represents a receptacle of suitable proportions, open at one side, and provided at that side with a frame 2, hingeably connected therewith at one of its edges. Within said receptacle are rotatably mounted a pair of rollers 3 and 4, in vertical alinement near the front of the receptacle, said rollers being provided at their ends with sprocket-wheels 5 and 6, engaged by a pair of corresponding sprocket-chains 7. Said chains also pass over the ends of a roller 8 journaled in the upper part of the receptacle, and downwardly beneath an idler roller 9, the shaft of which is supported in bearings 10 fixed on rods 11, vertically slideable in perforated brackets 12 and 13 secured to the side of the receptacle. Between the bearings 10 and the

brackets 12 is interposed a pair of extensible coiled springs 14, which exert a downward tension on the roller 9, and aid in holding the chains 7 in a taut condition.

Fixed on the inside of the chains 7 at regular intervals are pairs of sockets 15, adapted to hold at their ends clamp-plates 16 and 17, united by hinges 18. Fixed to the clamp-plate 16 is a plate 19, between which plate and the plate 16 is secured one end of an apron section 20, formed of canvas or other suitable material. The plates 16 and 17 are held normally in clamping position by means of spring metal clips 21, removably seated thereon. The opposite end of the canvas 20 is secured between a clamp-plate 22 and plate 23 fixed thereto, the plate 23 being connected with a similar plate 24 by means of hinges 25. The ends of the plates 22 and 24 are adapted to be loosely held in pairs of sockets 26 fixed on the inside of the chains 7, and are held in closed position by means of spring clips 27. The clamp-plates 17 and 24 have a central flexible connection by means of a spring-rod 28 loosely held at its ends in sleeves 29 fixed to the plate 24 and provided centrally with a plate 30 having a key-hole opening 31 adapted to receive a button 32 on the adjacent plate 17. For convenience in operation the plate 30 is provided with a tab 33. In case the canvas 20 is a little looser on one side than on the other the clamp-plates at the upper end thereof, by reason of the flexible connection just described, readily adjust themselves to such variation, and if necessary one end of such plates is permitted to precede the other end slightly. A slight separation or wider spacing of the clamp-plates at the upper end of the canvas from those at the lower end of the next adjacent section is also rendered possible. The clamp-plates 16 and 17 are given a semi-rigid connection with the sockets 15 by means of extensives of the pintles of the hinges 18 into spring-rods 34, which are normally held in depressions in the lower faces of the sockets.

In the picture business hereinbefore referred to it is usual to display advertising matter for three picture plays, and my machine is preferably provided with three of the canvas sections 20, although a larger number can be used, if desired. This is made possible by the use of the idler roller 9, which not only assists in keeping the

chains 7 in taut condition, but makes it possible to use an increased length of such chains so as to accommodate the desired number of sections.

5 35 represents a poster, which is held in place by having its upper and lower ends secured between the clamp-plates at top and bottom of the section 20. This is accomplished while the canvas is removed 10 from the machine and the clips 21 and 27 removed, permitting the opening of the clamp-plates. The poster sheet is then placed therein, the clamp-plates closed, and the clips secured thereon. The lower plates 15 are then slipped into the sockets 15, which are positioned at the lower part of the machine, and the upper clamp-plates slipped into the sockets 26. The section is then connected at top and bottom with the adjacent 20 sections and is ready for operation. By providing the receptacle 1 with a hinged frame 2, the placing and replacing of the posters can be readily carried on at the front of the machine, by swinging the frame to 25 one side for that purpose.

36 represents a base for the machine, in which is journaled a shaft 37, to which power may be applied in any suitable manner, but preferably from an electric motor, 30 on account of the small amount of space occupied thereby. Fixed on the shaft 37 is a segment gear wheel 38, adapted to intermittently actuate a gear-pinion 39 on a rotary shaft 40. On the opposite end of the 35 shaft 40 from the pinion 39 is a gear-wheel 41, in mesh with a pinion 42 on a rotary shaft 43 upon which the roller 3 is mounted. A continuous rotation of the shaft 37 will thus impart an intermittent movement 40 to the roller 3 and chains 7. The timing of the mechanism is such that the movement of the chains is interrupted at a time when one of the canvas sections and poster supported thereby is fully disclosed at the front of the 45 machine, such poster being exhibited for a pre-determined length of time, and then replaced by the next succeeding poster.

The frame 2 is constructed of suitable size to conceal the mechanical parts of the 50 device, when closed, and is preferably provided with a transparent glass. The poster will thus be inclosed between the canvas section in rear and the glass in front, which will aid in holding the poster in proper position while being exhibited.

While my invention has been shown and 55 described herein as being of special use in connection with picture shows, it can be adapted for use with other advertising matter. By a slight adaptation the number of poster supporting sections can be increased, and the machine varied in size and proportions, so as to render the same useful in the display of a series of cards for window advertising.

What I claim as my invention, and desire to secure by Letters Patent of the United States, is:

1. A poster display machine, comprising a receptacle; continuous conveying mechanism operatively mounted therein; a plurality of flexible poster supporting sections; clamp-plates secured to the ends of said sections and yieldingly connected at their ends with said conveying mechanism; means for a yielding connection between said sections; and mechanism for giving an intermittent movement to said conveying mechanism. 70

2. In a machine of the class described, a receptacle; rollers mounted therein and provided with chain carrying means; a pair of parallel chains carried by said rollers; pairs of clamp-plates flexibly attached to said chains and yieldingly connected; flexible sections secured at their ends to said clamp-plates; means for holding said clamp-plates in closed position; and means for suitably actuating said rollers. 80

3. In a machine of the class described, a receptacle; continuous conveying mechanism mounted therein; a plurality of flexible poster carrying sections; clamp-plates attached to said sections, and having a flexible connection at their ends with said conveying mechanism; central pivotal means of connection between said clamp-plates and the clamp-plates of the adjacent sections; and mechanism for giving to said conveying devices an intermittent movement. 90

4. In a machine of the class described, a receptacle, provided with a hinged frame at the front side; rollers mounted in said receptacle and provided with chain carrying means; a pair of chains carried by said rollers; a plurality of flexible sections; clamp-plates secured to opposite ends of said sections, those at one end thereof having a yielding connection with said chains and at the other end thereof a sliding connection with said chains; central yielding connecting means between said clamp-plates and the clamp-plates of the adjacent sections; and mechanism for imparting to said conveying mechanism an intermittent movement. 100

5. A machine of the class described, comprising a receptacle and swinging frame therefor; rollers mounted therein and provided with chain carrying means; a pair of chains carried by said rollers; a plurality of flexible sections; clamp-plates secured to one end of each of said sections provided at their ends with spring catches; sockets secured to said chains, adapted to receive the ends of said clamp-plates and be engaged by 115 said spring catches; clamp-plates on the opposite ends of said sections; sockets secured to said chains and adapted to receive the ends of said last-named clamp plates so as to permit a lateral movement thereof; a spring 120

125

130

connected with said last-named clamp-plates at a central point thereof; a plate fixed to said spring; means of engagement of said plate with the clamp-plates of the adjacent section; and mechanism for imparting to said rollers an intermittent movement.

6. In a device of the class named, a poster supporting means comprising a flexible section; plates secured to the ends thereof; 10 similar plates hingeably connected with said

first named plates, and adapted to be held in clamping relation therewith, to hold the ends of a poster; and means for holding said plates in clamping position.

In testimony whereof I affix my signature 15 in presence of two witnesses.

GEORGE F. HAVENS.
